UNITED STATES PATENT OFFICE.

CYRENUS WHEELER, JR., OF AUBURN, NEW YORK.

GRAIN-BINDER FOR HARVESTERS.

SPECIFICATION forming part of Letters Patent No. 321,467, dated July 7, 1885.

Application filed January 11, 1881. (Model.)

To all whom it may concern:

Be it known that I, CYRENUS WHEELER, Jr., of the city of Auburn, in the county of Cayuga and State of New York, have invented 5 certain new and useful Improvements in Grain-Binders for Harvesters; and I do hereby declare that the following is a full, clear, and exact description of the same.

In the description reference will be made to 10 the drawings accompanying the same, making part of this specification, in which—

Figure 1 is a side view of the binder as it appears applied to a harvester. Fig. 2 is an end view of the same, looking from the front 15 of the machine, the cord-carrying arm being up. Fig. 3 is a similar view, with the cord-carrying arm down. Fig. 4 is a plan or top view of a portion of the knotter-carrying arm, the cam-frame, and parts of the compressing devices. Fig. 5 is an end view of the same parts. Fig. 6 is a top or plan view of the grain-receiving platform, and the mechanism for operating the bundle-arrester in connection with 20 the knotter-carrying arm, the platform being broken away to show the same.

The same letters, where they appear in the several figures, indicate like parts of the machine.

My improvements are applicable to that 30 class of machines in which the binder-arm vibrates vertically and swings horizontally, sweeping the grain to be bound outward across the binding-table, and returning above the accumulating grain.

The band-securing mechanism is carried on 35 an arm swinging in unison with the horizontal vibration of the binder-arm, and is operated by cams beneath the binding-table.

As the machine here shown is in many of 40 its features identical in every respect with that shown and described in Patent No. 266,001, granted to me October 17, 1882, only so much of it will be described as may be found necessary to a clear understanding of the devices 45 embraced in this application.

The nature of this invention consists in combining with a horizontally-moving knotter-arm and a vertically-oscillating and horizontally-vibrating binder-arm, a laterally-projecting rigid arm and a hinged compressing arm 50 connected by a spring to give the hinged arm an outward deflection, a yielding and adjust-

able compressing strap or flexible connection between the hinged compressing-arm and binder-arm, compressing-strap, automatic let-off devices for releasing the tension of the compressing-strap at the proper time and automatically taking up the slack in the same, and means by which the let-off devices can be set to let off at different points in the outward movement of the binding mechanism; also, in a shield-plate having projecting fingers, and secured to the knotter-carrying arm; also, in a compressor-arm pivoted to the knotter-carrying arm below the grain receiving and binding platform; also, in a rod, a lever, a roller, and a fixed camway for operating said compressing-arm, and a spring to make the compressor-arm yielding; also, in devices for preventing the return of the bundle in the backward movement of the binding devices; also, in a swinging lever and pivoted switch below the platform, and a roller on the knotter-arm for working the bundle-arrester.

In carrying out the invention an arm, A⁵, 75 is firmly fastened to the binder-arm C, so as to project laterally from it. It is forked at that end which is connected to the arm C, so as to give it firmness, and is curved downward at its projecting end. To this arm is hinged, at 80 its outer end, a compressing-arm, B⁵. This arm has an enlarged opening through it at C⁵, in which is pivoted a roller, D⁵. The arm B⁵ has an extension-piece, E⁵, carried beyond the hinged point, and to this is connected one end 85 of a spiral spring, F⁵, the other end of the spring being connected to an ear-piece, G⁵, on the rigid arm A⁵. This spring serves to keep the arm B⁵ extended outward, as shown in Figs. 1 and 2, when not otherwise restrained. An ear, H⁵, 90 projects from the outside of the compressing-arm B⁵, in which is a hole nearly parallel to the arm, and in which is inserted a rod, I⁵, so as to slide freely. On the upper end of the rod is cut a screw-thread which has a thumb-nut, J⁵, for lengthening or shortening the distance between the nut and ear in which it slides, to give greater or less tension, as desired, to the spring F⁵, which surrounds said rod and bears against said nut and ear. To 100 the lower end of this rod is connected a buckle, K⁵, or other convenient device, for connecting the compressing-strap L⁵ and adjusting its length at pleasure. This strap extends from the

buckle K⁵ down through the opening C⁵ and under the roller D⁵ in the arm B⁵, and across to the binder-arm C, passing under a roller, M⁵, attached to the needle B, and is fastened 5 at its end to a bell-crank lever, N⁵, which is pivoted at O⁵ to the cord-carrying arm C.

To the upwardly-projecting arm of the bell-crank lever, at P⁵, is pivoted the link-rod Q⁵. At b⁵, on the extension-piece X of the pitman 10 B', is a projecting pin, on which a notch, a⁵, in the link-rod Q⁵ drops, and which serves to hold said rod until released, as will hereinafter be explained. A guide-piece, c⁵, attached to the rod Q⁵ on the outer side of the piece X, 15 serves to keep said rod Q⁵ in proper position to drop onto the pin with certainty. This link-rod extends beyond the point of connection of the guide c⁵, and has a series of holes, d⁵, for inserting the hook-end of the link e⁵, 20 the other end of which link hooks into one of a series of holes, f⁵, in the bell-crank g⁵, which is pivoted at h⁵ to a fixed ear on the foot of the stand which supports the vertical rock-shaft T. The pivot-pin e⁵ of the arm Z is 25 made to project from the jaws of the vertical rock-shaft far enough to strike the downwardly-projecting arm i⁵ of the bell-crank g⁵.

The shield-plate S has fingers j⁵, projecting outward above the plane of the cutters, which 30 serve to hold the grain up against the force of the compressing devices and bring the bundle, when formed, into a more compact state, as will be hereinafter explained.

An ear-piece, k⁵, is bolted, or otherwise 35 fastened, to the knotter-carrying arm A, or knotter-stand l. To this ear-piece is pivoted, at l⁵, a lever or compressing-arm, R⁵. This arm projects outward when down and at rest. It also has a short branch, m⁵, standing at a little 40 less than right angles thereto, the arm and its branch both projecting from the pivot. This branch m⁵ has a hole through it for the end of the rod n⁵ to play freely in. This rod is rounded for a portion of its length, and has a 45 coiled spring, o⁵, placed on it between the branch m⁵ and its shoulder p⁵. A pin passing through the end of the rod n⁵, above the arm m⁵, holds the same in place. The lower end of the rod n⁵ is pivoted to one end of a short lever, 50 q⁵ at r⁵, the other end of which lever is pivoted to the ear-piece k⁵ at s⁵. On the side of the lever q⁵, opposite the rod n⁵, is a friction-roller, t⁵. Upon a fixed camway or rail, S⁵, supported by the cam-frame R', to which it is attached, the 55 roller t⁵ travels in the movement back and forth of the knotter-carrying arm A. This camway is arranged parallel to the path in which the knotter-arm moves, except at its outer end, which is bent down nearly at right 60 angles, in order to give the arm R⁵, which receives its upward and downward motions from the camway through the lever q⁵ and rod n⁵, a quick elevation and depression. This camway or rail S⁵ may be cast in one piece with 65 the cam-frame R', if preferred, instead of being bolted to it, as here shown. The arm R⁵ is bent backward from its pivot-point, so that

when elevated it will stand between the fingers j⁵.

In order to provide against the return of 70 the bound bundle in the return movement of the binding mechanism, which in tangled grain it is liable to do, and thus obstruct the proper working of the compressing-arm B⁵, a bundle-arresting mechanism is provided, 75 which consists of an arm, T⁵, pivoted by a bolt, u⁵, to lugs on the upper surface of the grain-platform G' at its forward outer corner. This arm T⁵ is forked at its pivot end to give it a broad bearing. One of these forks or branches extends beyond the pivot u⁵, and has a hole in it at v⁵ for connecting a link-rod, U⁵, the other end of which rod is connected to the ear w⁵ on the swinging lever V⁵, arranged below the platform G' and pivoted at B⁶. To this lever V⁵ is connected, by a vertical pivot, x⁵, a switch, W⁵, and to the lower end of the pivot x⁵ is fastened a short arm, z⁵, to which one end of a coiled spring, y⁵, is fastened, the other end of said spring being fastened to an ear-piece, X⁵, 90 on the swinging lever V⁵. Another spring, Y⁵, has one of its ends connected to the same ear, and its other end to the under side of the platform. An arm, Z⁵, is fastened to the knotter-carrying arm, and to the under side of its 95 projecting end is pivoted a roller, a⁶. The swinging lever V⁵ is supported at its outer end by a guide-piece, A⁶, which serves to hold it up in working position. The bundle-arresting arm T⁵ is inclined upward and backward, 100 and extends to a point nearly over the edge of the slot or opening through the platform G'. It is bent so as to stand with its end vertical, and when down its pointed end rests in a socket, b⁶, formed in the platform G'. 105

Having described the construction of these several improvements and the mode of application to the machine, I will now describe their operation. The cord for binding is shown wound on a spool and supported on 110 an arm instead of being taken from the ball carried in a box. In other respects the application of the cord to the sheaves and needle-arm and knotting devices is the same as in my said patent. As the needle B and binder-arm C descends to encircle the gavel with the cord the notch a⁵, in the link-rod Q⁵, locks onto the pin b⁵, in the extension-piece X of the pitman B', and takes up the slack of the compressing-strap L⁵, attached to the bell-crank N⁵. As the arm continues to descend the strap L⁵ presses on the gavel and brings the bundle into compact shape, aided by the pivoted lever R⁵, which is actuated through its connections by the roller t⁵ and its camway or track S⁵, as seen in Fig. 3. As the 115 binder-arm and knotter-arm move outward the knotting mechanism performs its functions of tying the knot, and the cord is severed for releasing the bundle in the same manner 120 as described and shown in my said patent. The compression is kept up until the knot is formed, at which point the downwardly-projecting branch i⁵ of the bell-crank g⁵ is struck 125

by the projecting pivot-pin e^5 , carried by the vertical rock-shaft T . The long arm of the crank is thus thrown upward, and through the connecting-link e^5 the rod Q^5 is raised and released from the pin b^5 , and the bell-crank N^5 is free to swing on its pivot O^5 , thus slackening the compressing-strap L^5 . The arm B^5 , being freed from the restraint of the connecting-strap L^5 , is, by the action of its spring F^5 , swung outward, and the bundle, being released from pressure, is free to expand. This let-off motion is automatic, and can be set to let off and permit the bundle to expand at different points of the movement of the binder mechanism by changing the ends of the rod e^5 to the different holes d^5 in link-rod Q^5 and holes f^5 in the bell-crank g^5 , the outer holes causing it to let off earlier, the inner holes later. As the bundle is still farther moved outward the roller t^5 passes off of its camway S^5 and the arm R^5 drops down to allow the discharge of the bundle over it, as seen in Fig. 2. The bundle-arresting arm T^5 in the movement of the knotter-carrying arm outward is elevated, as seen in Fig. 3, by the roller a^6 on the arm Z^5 , passing along the outer side of the swinging lever V^5 , (see Figs. 3 and 6,) and is held in an elevated position until the completed bundle is carried by the needle and binder-arm beyond its point when the roller passes off of the outer end of the lever V^5 and the arm T^5 drops by its own gravity, aided by the spring Y^5 , and holds the bundle C^6 , as shown in Fig. 2. This holding of the bundle is important, as in using the machine in badly-tangled grain, the separation of the bound bundle from the grain remaining and accumulating on the table would otherwise be imperfect, the straws in the new gavel being but partially separated from the bundle during the movement of the knotter-arm and binder-arm back with the cord extended between the two, which carries back the grain and brings it into position for the compressing-arm B^5 to embrace the next bundle. The bundle-arrester, in its operation, effectually prevents the return of the bound bundle, and leaves an unobstructed space for the operation of the compressing-arm. In the return movement of the knotter-carrying arm the roller a^6 passes back inside of the swinging lever V^5 , as shown in Fig. 1 and in dotted lines in Fig. 6. In this return movement of the roller it presses back the pivoted switch W^5 , and when it passes off of its free end the spring y^5 , by its action on the switch through the arm z^5 , to which it is attached, throws the switch in again, so that in the return movement the roller a^6 must pass along the outer side of the switch to the outer side of the lever V^5 , which it will draw inward, thus raising the bundle arresting arm T^5 , this arm being brought to its full height soon after the roller passes from the switch to the lever. The lever is of the proper curve to hold the arm T^5 elevated until the bundle is delivered beyond the point of the same.

The different positions of the knotter-carrying arm and the devices for actuating the bundle-arrester are shown in full lines and in dotted lines in Fig. 6.

The bundle-arrester may be materially modified in its construction and application without changing the nature of the invention. I have used it for the same purpose applied below the platform, the point being automatically projected up through the platform at the proper time, and far enough to effectually hold the bundle, as shown in my application, No. 44,784, filed October 29, 1881.

The pivoted compressing-arm R^5 also forms an important feature in conjunction with the compressing devices carried on the binder-arm, as well as with the cord itself. This arm R^5 is brought into its elevated position on the return movement of the swinging binding mechanism at the earliest moment it can be done without seriously interfering with the bound bundle, which is as soon as the end of the arm R^5 has passed the center of the bundle. (See Fig. 2.) By thus early elevating it, it materially aids in relieving the cord from the strain that in badly-tangled grain would be thrown upon it, thus permitting the use of cord of barely sufficient strength to hold safely the bundle when bound, but not strong enough to withstand the strain of returning against the accumulating gavel when the separation in tangled grain is imperfect. This arm R^5 , by means of the coiled spring o^5 on the rod n^5 , will yield to the varying size of the bundles. This arm R^5 , in its application, may also be varied, and I have done so in different ways, as by attaching it to a long pivot or shaft and extending the same backward far enough to be operated by a roller and track on the cam-frame, as shown in my said application, No. 44,784.

As the shield-plate S is elevated above the plane of the binding-platform, for the purpose of relieving the platform from the pressure and friction of the bundle when being bound, the fingers j^5 , connected with the shield, serve the important purpose of holding the bundle up under the severe pressure brought upon it. Without such fingers a portion of the straw forming the bundle would be pressed down in front of the shield-plate S , and the bundle, when completed, would be imperfect in form, taking more length of cord to encircle it, and when released and assuming a more rounded form would not be so snugly bound.

By the use of the compressing-arm B^5 and compressing-strap L^5 and their connecting devices, a movement very similar to that of the human arm is attained, giving the machine a wide range of capacity for binding properly bundles varying in their diameters from six inches to fourteen inches without perceptible difference in their compactness, and with somewhat diminished compactness bundles from six inches down to one inch in diameter. The coiled spring e^5 on the rod I^5 , which connects with the strap L^5 , permits the latter to yield

to the varying size of the bundles, and, by means of the buckle K^5 and nut J^5 , it may be adjusted to give any desired pressure to any size of bundle. These compressing devices are shown in connection with the let-off motion; but this can be dispensed with and still the compressing devices would work very satisfactorily. I have used machines with the strap attached to the ear that carries the roller M^5 , which ear is attached to the needle-arm B , instead of attaching it to the bell-crank N^5 . The machine will also perform very satisfactory work without the arm R^5 ; but a stronger cord will be required than is necessary when it is used. In practical tests, made with a full-sized machine, constructed as shown and described, it is found that cord that will break with a strain of sixty-five pounds and averaging seven hundred and twenty-five feet in length to the pound, will produce satisfactory work, and that with the same cord in the same machine, with bundle arresting and compressing devices removed, and with all the tension it will bear applied to the cord, it will require from fifteen to twenty per cent. more cord to bind the same amount of grain in a less satisfactory manner. In practice, the bundle C^5 remains in the position shown in Fig. 2, until the succeeding bundle is brought forward, when the arm B^5 is brought against it and pushes it from the platform. The compressing devices and the bundle-arresting mechanism are applicable to other machines of different construction, and parts of the same may be applied to work effectually without embracing the whole.

Having thus fully described the improvements embraced in this application, what I claim as new, and desire to secure by Letters Patent, is—

1. The compressing devices carried on the binder-arm, in combination with the horizontally-oscillating knotter-arm and the shield-plate having projecting fingers, substantially as described.

2. The combination, with the binder-arm, the laterally projecting compressing-arm connected with and carried by said binder-arm, and the compressing-strap connecting said binder-arm and hinged compressing-arm, of the automatic let-off, arranged and operating substantially as described.

3. In combination with the binder-arm, the hinged compressing arm secured to and carried by said binder-arm, the compressing-strap connecting said binder-arm and hinged compressor-arm, the automatic let-off, and means by which the latter is operated to automatically take up the slack of the compressing-strap, substantially as described.

4. In combination with the compressing-strap connecting the hinged compressor-arm

and binder-arm, the automatic let-off, and means by which it can be set to let off at different points in the outward movement of the binder-arm, substantially as described.

5. The vertically-vibrating compressor-arm hinged to the horizontally-vibrating knotter-carrying arm below the grain platform, and means for operating it, in combination with the vertically-oscillating and horizontally-swinging binder-arm, substantially as described.

6. The compressor-arm, pivoted to the knotter-carrying arm below the grain-receiving platform, in combination with the rod, lever, and fixed cam for operating the same, substantially as described.

7. In combination with the compressor-arm pivoted to the knotter-carrying arm below the grain-receiving platform, and means for operating it, as described, the knotter shield-plate having projecting fingers arranged above the plane of the grain-receiving platform, substantially as and for the purpose described.

8. The vertically-oscillating and horizontally-swinging binder-arm, the laterally-projecting rigid arm, the compressing-arm hinged thereto, the compressing-strap connecting the binder-arm and compressing-arm, the compressor-arm pivoted to the knotter-carrying arm below the platform, the fixed camway, and connecting devices for operating the same, the whole arranged and combined for joint operation substantially as described.

9. The combination of the compressor-arm pivoted to the knotter-carrying arm, the rod connecting it with its operating-lever, and the spring, substantially as and for the purposes stated.

10. The bundle-arresting arm, in combination with the horizontally-oscillating knotter-carrying arm, the compressor-arm pivoted thereto, and the vertically-oscillating and horizontally-swinging binder-arm, substantially as and for the purposes stated.

11. The grain-receiving platform, the bundle-arresting arm hinged to it, the horizontally-swinging lever arranged below the platform, the link connecting said arm and lever, and the roller carried by the knotter-arm, arranged and combined for joint operation as shown and described.

12. The combination of the grain-receiving platform, the bundle-arresting arm hinged to it, the horizontally-swinging lever below it, the link connecting said arm and lever, the roller carried by the knotter-arm, and the vertically-pivoted switch carried on the swinging lever, substantially as described and shown.
